UNITED STATES PATENT OFFICE.

WALKER S. ESTES, OF TULSA, OKLAHOMA.

DERRICK STRUCTURE.

Application filed April 3, 1923. Serial No. 629,689.

To all whom it may concern:

Be it known that I, WALKER S. ESTES, a citizen of the United States, and a resident of Tulsa, in the county of Tulsa and State 5 of Oklahoma, have invented certain new and useful Improvements in Derrick Structures, of which the following is a full, clear, and exact description.

My invention relates to improvements in 10 derrick structures, and one of the advantages of the invention resides in the provision of a vertically movable top structure or header, whereby reinforcing or doubler legs of greater length than the legs of the 15 derrick proper may be quickly and easily applied to or removed from the derrick proper.

Another advantage of the invention resides in the complete elimination of bolts or rivets passing through the derrick legs 20 and the doubler or reinforcing legs, and in substituting therefor clamping means for connecting the derrick legs and reinforcing legs.

The particular improvements to be specifically described hereinafter are adaptable 25 to use in connection with any derrick structure which at times is employed for light work, and at other times for heavy work; but the invention is especially designed for 30 use in connection with wells, such as oil, gas and artesian wells, and the construction will be particularly described herein as used in the oil and gas fields.

In the operation of drilling a well it is 35 necessary to employ a very strong and heavy derrick, but when the drilling is completed a relatively light derrick is sufficient for pumping purposes. The most usual practice has been to originally employ a heavy and 40 expensive derrick for the drilling operation, and to continue to use the same derrick for the light work of pumping until the derrick is no longer serviceable because of deterioration, etc., whereupon it is replaced by 45 an ordinary light pumping derrick.

In other instances, where the wind hazard is too great, it has been the practice to 50 remove the heavy derrick upon completion of the drilling operation, and erect a pumping derrick in its place.

It is obvious that either of the practices outlined above involves a vast waste of time, labor and money, and that great economies would be accomplished by some practical reinforcing means, so that a light pumping 55 derrick would be originally installed, and which could be reinforced to render it sufficiently strong for the heavy work of drilling, and which would permit the removal of the reinforcing means upon completion of 60 the drilling, thereby leaving the ordinary light pumping derrick. The reinforcing means, when removed, would be available for use in connection with other drilling operations, or for any other heavy work, such 65 as to pull casing.

The present invention does not relate to the mere use of reinforcing legs or stiffeners, but the present invention does relate broadly to means whereby the use of reinforcing legs is rendered practical in the ordinary field practice. Prior to the present invention it has been suggested to use reinforcing legs extending the entire distance 75 from the header to the base, and to secure 70 these reinforcing legs to the derrick legs proper by means of bolts. The purpose, of course, of such a structure is to divide the load between the derrick legs and the reinforcing legs.

In order to emphasize the advantages of the present invention, it may be well to briefly mention a few of the disadvantages of the reinforcing structure outlined above, which disadvantages render it entirely impractical for ordinary field operations.

If the reinforcing legs are to carry part of the load and the derrick legs are to carry part of the load, it is apparent that the reinforcing legs must be of exactly the same 90 length as the derrick legs, and it is equally apparent that in actual operation the legs would very seldom, if ever, be of exactly the same length. Even if the legs are of the same length, a slight distortion of the derrick legs or the reinforcing legs will vary 95 their effective length, thereby losing to a large extent the function of dividing the load. Further, if the reinforcing leg is slightly longer than the derrick leg, it can- 100

not be applied, because of the fixed header. On the other hand, if the reinforcing leg is slightly shorter than the derrick leg it entirely loses its function of dividing the load, and becomes nothing more than a mere stiffener.

Ordinary reinforcing legs are built in sections, each section having at its upper end a socket which is adapted to receive the lower end of the section above. It will be understood that to erect these reinforcing legs each section must be raised and dropped into its socket. When the top section is reached it cannot be applied without first dismantling the top structure of the derrick; and to remove the top reinforcing leg sections the derrick top structure must be again dismantled for it is impossible to lift the sections from their sockets on account 20 of the fixed header.

For the purpose of securing the reinforcing legs to the derrick legs both legs were provided with holes adapted to receive bolts passing through both legs. Such a structure 25 is highly impracticable in ordinary use, for it is apparent that for many reasons, such as the slightest distortion of either leg, the holes would not properly align, thereby rendering the securing means inoperative.

30 I will now describe the structure which entirely eliminates the above and other disadvantages; reference being had to the accompanying drawings, in which:

Figure 1 is a side view of a light pumping 35 derrick provided with a vertically movable top structure or header.

Figure 2 is a side view of the same derrick, but with the header in elevated position, and with the reinforcing legs or doublers, applied to the derrick.

Figure 3 is a side view, on a somewhat larger scale, of the upper portion of the derrick, and doubler legs ready to be applied, and showing in broken lines the position of 45 the header and doubler legs when the latter have been mounted in place on the derrick.

Figure 4 is a fragmentary view more clearly showing the sliding connection between the header and the derrick structure.

50 Figure 5 is a horizontal sectional view taken through one of the derrick and reinforcing legs. This figure clearly shows how the outer legs abut against the ordinary bolts securing the sections of the inner legs, thereby entirely eliminating the use of spacers or fillers; and

Figure 6 is a fragmentary view representing any ordinary base structure for supporting the derrick and reinforcing legs.

60 Referring to the drawings more in detail numeral 1 indicates the legs of any ordinary light derrick, the legs being formed in sections, as usual, and connected in any desired and ordinary manner. The means

I have shown for bracing the legs comprises 65 diagonal braces 2, girts 3, and vertical braces 4. It is to be understood that the body of the derrick structure may be of any desired type or construction, and, as the particular construction thereof forms no part of the 70 present invention, the foregoing brief description will be sufficient.

One of the radical changes in derrick construction included in the subject-matter of the present invention is the manner of 75 mounting the header or top structure of the derrick. In prior derrick constructions the header is fixed to the derrick body so that it is immovable with respect to the body without dismantling the header. In the 80 present construction, however, the header is mounted for vertical sliding movement with respect to the derrick body.

The invention is not, of course, limited to 85 the specific means illustrated for accomplishing the sliding connection between the header and derrick body; but, on the contrary, the invention relates broadly to a header movable with respect to the derrick body and it is to be understood that the invention includes any and all means by which this may be accomplished. I will now describe the specific means illustrated herein.

90 The header is indicated generally by the numeral 5, and it may be of the conventional form employed in steel derricks, or it may be of any other form preferred. Attached to the header 5 are the relatively short leg sections 6, and these leg sections are provided with one or more slots 7, three of the 95 slots being illustrated in the drawings. Numeral 8 indicates any ordinary gusset plate to which the diagonal braces 2 are attached, and the lower portion of the gusset plate being riveted to the upper end of the leg sections in the usual manner. The upper portions of the gusset plates are not fixed to the relatively short leg sections 6, but have a sliding connection therewith. This 100 sliding connection is accomplished by providing the upper portion of the gusset plates with one or more pins which pass through the slots 7 provided for that purpose, and are secured in the gusset plates. The pins 105 may be in the form of bolts or rivets, and are indicated by numeral 9. It is thus apparent that the header, or top structure of the derrick, is free to be moved vertically to the extent of the length of the slots 7, and, of course, the slots may be of any desired length.

110 As previously stated herein, the specific means for slidably mounting the header is for purposes of illustration only, for it is readily apparent that numerous other means 115 may be devised for accomplishing the same purpose. For instance, the derrick legs may be slidably connected directly to the header 120

structure, thereby eliminating the relatively short leg sections; or, instead of providing the short leg sections with slots, it may be preferred to provide the slots in the gusset plates and have the engaging pins carried by the short leg sections; or the gusset plates may be fixed to the relatively short leg sections and have a sliding connection with the next lower leg sections, or the pins and slots may be eliminated entirely by the use of some socket construction which would support the header in such manner that it would be free to be raised or lowered whenever desired. These few modifications are mentioned merely to show that the specific structure may be varied in a great many ways, and to emphasize the fact that the present invention contemplates any manner of slidably mounting the header or top structure relative to the derrick proper.

The reinforcing legs, or doublers, are indicated by numeral 10, and it is to be noted that these legs are slightly longer than the derrick legs. The sections forming the reinforcing legs are united in any desired manner, and I have, therefore, merely illustrated generally herein an old and well known form of socket connection. The sockets are formed by riveting an angle bar (not shown) on the interior of the leg section adjacent the top thereof, so that it will extend above the top of the section, and on the exterior of the leg section are riveted straps 11, also extending above the top of the section, and thereby forming a socket to receive the lower end of the section next above. Bolts are then employed to secure the lower end of the upper section to the socket members. The sections are thus arranged in an end-to-end abutting relation, so that the load is carried directly by the leg sections, and the bolts and rivets are not subjected to unnecessary stresses. The end-to-end abutting relation of the leg sections is also old and well known in the prior art, and per se constitutes no part of the present invention. In so far as the present invention is concerned, the reinforcing leg sections may be formed and united in any manner desired.

The operation of the apparatus thus far described is as follows:

When drilling operations are to commence the light pumping derrick with movable header is installed. This derrick is not strong enough for the heavy work of drilling, and consequently the reinforcing legs, or doublers, are applied before starting the drilling operation. As previously stated herein, and as clearly illustrated in the drawings, the reinforcing legs are slightly longer than the derrick legs; therefore, to mount the doublers in place it is only necessary to raise the header to the dotted line position in Figure 3, apply the doubler sections, and then lower the header so that it rests on the doublers. When the doublers have been applied, the lower ends of the relatively short leg sections of the derrick are no longer in abutting relation with the upper ends of the next lower sections, and thus it is obvious that the derrick legs carry no part of the load; the entire load being carried solely by the reinforcing legs.

It is also apparent that the successful operation of this apparatus is in no way dependent upon the exact length of the derrick legs or reinforcing legs; for it is immaterial whether the difference in length between the two legs is very slight or considerable, for, the header being movable, it is only necessary to raise the header sufficiently to take care of the difference in length.

It is also apparent that under no circumstances is it possible for the reinforcing legs or doublers to become mere stiffeners, for the reinforcing legs are longer than the derrick legs, and obviously this precludes any conditions that would take from the doublers their intended function and reduce them to mere stiffeners.

When the drilling operation has been completed the doublers are salvaged, and the original light pumping derrick is left in place for the pumping operation. It is to be noted here that no difficulty will be encountered in salvaging the doublers, for it is only necessary to raise the header and remove the sections forming the doublers. When the doublers have been removed from the derrick they are ready for use in any other drilling operation; and, of course, they are also available for further use on the same derrick when it is again to be employed for heavy work, such as pulling casing.

I will now describe the means for securing the reinforcing legs to the derrick legs. As stated hereinbefore, it has been suggested, prior to the present invention, to secure reinforcing legs to the derrick legs by means of bolts. It has also been indicated hereinbefore that such a construction is highly impracticable for various reasons, but particularly so because of the fact that the slightest distortion of either the derrick leg or reinforcing leg will prevent the bolt holes from properly aligning, and thereby render the securing means inoperative. In the present construction I have entirely eliminated the use of bolts or rivets for securing the reinforcing legs to the derrick legs, and in place of such securing means I have substituted a clamping device, and I have also entirely eliminated the use of spacers or fillers. By referring now to Figure 5, it will be apparent that I do not employ any spacers or fillers between the derrick legs 1 and the reinforcing legs 10, but that, on the contrary,

the reinforcing legs abut directly against the bolts which are used for the purpose of connecting the sections of the derrick legs, and which bolts are actually a part of the 5 light derrick; the bolts being indicated by numeral 12. While I prefer the construction herein described, it will be understood that ordinary spacers or fillers may be employed, if desired. At suitable intervals 10 along their lengths the reinforcing legs and derrick legs are clamped together by means of bent bolts 13, the ends of which pass through apertures in a suitable plate or bar 14, the various parts being securely clamped 15 together by setting up on the nuts 15 engaging the threaded ends of the bent bolts. Such a construction presents a ready and practical means for tying the doublers to the derrick legs and entirely eliminates the 20 disadvantages that are apparent in a construction in which the legs are intended to be secured together by means of bolts.

The base support and anchoring means constitute no particular part of the present 25 invention, and in Figure 6 I have, therefore, merely indicated a conventional form of mounting, comprising a concrete pedestal 16, to which is anchored the ordinary base plate 17; and angles 18 being employed for the 30 purpose of riveting the derrick legs to the base plates. It will be understood that the invention is by no means limited to any particular base or anchoring means, and any preferred form thereof may be employed.

35 In accordance with the patent statutes, I have described what I now believe to be the best embodiment of the invention, but I do not wish to be understood thereby as limiting myself or the scope of the invention, as 40 many changes and modifications may be made without departing from the spirit of the invention; all such I aim to include in the scope of the appended claims.

What I claim as new and desire to secure 45 by Letters Patent, is:

1. In a derrick, a body structure, and a top structure, said top structure being movable with respect to the body structure, and means other than the body structure for 50 supporting the top structure after it has been moved.

2. In a derrick, a body structure, and a top structure, said top structure being vertically movable with respect to the body structure, and means other than the body structure for supporting the top structure after 55 it has been moved.

3. In a derrick, a body structure, and a top structure, and a sliding connection between the top structure and body structure, whereby the top structure may be moved, and means other than the body structure for supporting the top structure after it has been moved.

60 4. In a derrick, a body structure, and a

header, said header being movably mounted on the body structure, and means other than the body structure for supporting the header after it has been moved.

5. In a derrick, a body structure, and a 70 header, said header being mounted for vertical movement on the body structure, and means other than the body structure for supporting the header after it has been moved.

6. In a derrick, a body structure, and a 75 header, and a sliding connection between the body structure and header, whereby the header may be moved, and means other than the body structure for supporting the header after it has been moved.

80 7. A derrick comprising a plurality of legs, a top structure carried by the legs, and a pin and slot connection between said legs and the top structure whereby the top structure may be moved, and means other than the body structure for supporting the top structure after it has been moved.

85 8. A derrick comprising a plurality of legs, a header, a plurality of legs carried by the header and co-operating with the derrick legs to support the header, said header and legs being movable with respect to the derrick legs, and means other than the derrick legs for supporting the header after it has been moved.

90 9. A derrick comprising a plurality of legs, a header, a plurality of legs carried by the header and co-operating with the derrick legs to support the header, said header and legs being mounted for free vertical 100 movement with respect to the derrick legs, and means other than the derrick legs for supporting the header after it has been moved.

10. A derrick comprising a plurality of legs, a header, a plurality of legs carried by the header and co-operating with the derrick legs to support the header, and a sliding connection between the derrick legs and the legs carried by the header, whereby the 105 header may be moved, and means other than the derrick legs for supporting the header after it has been moved.

11. A derrick comprising a plurality of legs, a header, a plurality of legs carried by the header and co-operating with the derrick legs to support the header, and a pin and slot connection between the derrick legs and the legs carried by the header, whereby the header may be moved, and means other 115 than the derrick legs for supporting the header after it has been moved.

12. A derrick comprising a set of legs, a header, a set of legs carried by the header and co-operating with the derrick legs to support the header, gusset plates fixed to one of said sets of legs, said gusset plates having a sliding connection with the other of said sets of legs, whereby the header may be moved, and means other than the derrick 125 legs for supporting the header after it has been moved.

- legs for supporting the header after it has been moved.
13. A derrick comprising a plurality of legs, a header, a plurality of legs carried by the header and co-operating with the derrick legs to support the header, gusset plates fixed to the derrick legs, said gusset plates having a sliding connection with the legs carried by the header, whereby the header may be moved, and means other than the derrick legs for supporting the header after it has been moved.
14. A derrick comprising a body structure and a top structure, and means for supporting the top structure independently of the body structure.
15. A derrick comprising a body structure and a top structure, and means other than the body structure for carrying the entire load of the top structure.
16. A derrick comprising a body structure and a top structure, and means removably connected to the body structure for carrying the entire load of the top structure.
17. A derrick, including a body structure and a header, said header being normally supported by the body structure, and means for supporting said header independently of the body structure.
18. A derrick, including a body structure and a top structure, said top structure being vertically movable with respect to the body structure, and reinforcing legs for supporting the top structure.
19. A derrick comprising a plurality of legs, a top structure mounted for free vertical movement on the derrick legs, and reinforcing legs for supporting the top structure, said reinforcing legs being of greater length than the derrick legs.
20. A derrick comprising a body structure and a top structure, said top structure being mounted for vertical movement on the body structure, reinforcing legs for supporting the top structure in an elevated position, and the body structure supporting the top structure in its lowered position.
21. A derrick comprising a body structure, a header movably mounted on the body structure, and reinforcing legs adapted to engage the header, said reinforcing legs being of greater length than the derrick legs.
22. A derrick comprising a plurality of legs, a header slidably mounted on the legs, reinforcing legs engaging the header, said reinforcing legs being of greater length than the derrick legs and carrying the entire load of the header.
23. A derrick comprising a plurality of legs, a header slidably mounted on the legs, reinforcing legs removably attached to the derrick legs, said reinforcing legs being of greater length than the derrick legs and engaging the header, whereby they carry the entire load of the header.
24. A derrick structure comprising a plurality of legs, a header mounted for vertical movement on said legs, reinforcing legs clamped to the derrick legs, said reinforcing legs adapted to engage the header.
25. A derrick structure comprising a plurality of legs, a header mounted for vertical movement on said legs, reinforcing legs clamped to the derrick legs, said reinforcing legs adapted to engage the header and being of greater length than the derrick legs.
26. A derrick structure comprising a plurality of legs, a header movably mounted with respect to said legs, reinforcing legs adapted to be removably secured to the derrick legs, the sole means for securing the reinforcing legs and derrick legs comprising a plurality of clamps.
27. A derrick structure comprising a plurality of legs, a header movably mounted with respect to said legs, reinforcing legs adapted to be removably secured to the derrick legs, the sole means for securing the reinforcing legs and derrick legs, comprising a plurality of clamps, said clamps including bent bolts embracing the reinforcing legs, and plates, said bent bolts being adjustably connected to the plates.
28. A derrick structure comprising a plurality of legs, a header movably mounted with respect to said legs, reinforcing legs adapted to be removably secured to the derrick legs, said reinforcing legs adapted to abut against the bolts connecting the sections of the derrick legs, the sole means for securing the reinforcing legs and derrick legs comprising a plurality of clamps, said clamps including bent bolts embracing the reinforcing legs, and plates, said bent bolts being adjustably connected to the plates.
29. A derrick comprising a plurality of legs, a top structure carried by the legs, a pin and slot connection between said legs and the top structure, reinforcing legs engaging the top structure and removably connected to the derrick legs, said reinforcing legs being slightly longer than the derrick legs.
30. A derrick comprising a plurality of legs, a header, a plurality of legs carried by the header and normally co-operating with the derrick legs to support the header, reinforcing legs of greater length than the derrick legs and removably connected thereto, said reinforcing legs adapted to engage the header and to maintain the legs thereof out of contact with the derrick legs.
31. A derrick comprising a plurality of legs, a header, a plurality of legs carried by the header and normally co-operating with the derrick legs to support the header, a pin and slot connection between the derrick legs and the legs carried by the header, reinforcing legs adapted to engage said header and to be removably connected to the derrick

legs, said reinforcing legs being of greater length than the derrick legs.

32. A derrick comprising a plurality of legs, a header, a plurality of legs carried by the header and normally co-operating with the derrick legs to support the header, gusset plates fixed to one set of legs, said gus-

set plates having a sliding connection with the other of said sets of legs, reinforcing legs adapted to engage the header and to be removably connected to the derrick legs, said reinforcing legs being of greater length than the derrick legs. ¹⁰

WALKER S. ESTES.
